FILAMENT STRUCTURE FOR ELECTRICAL
DISCHARGE DEVICESJoseph W. Skehan, Stamford, Conn., assignor to
Machlett Laboratories, Inc., Springdale, Conn.,
a corporation of Connecticut

Application May 19, 1945, Serial No. 594,688

7 Claims. (Cl. 250—27.5)

1

This invention relates to electrical discharge devices and is concerned more particularly with a novel cathode structure for use in such devices, which offers numerous advantages over prior structures, in that it is more rugged and simpler to manufacture. The new cathode structure may be advantageously employed in electron tubes of various kinds, but, since it is especially suited for use in rectifier tubes, an adaptation of the invention for that use will be illustrated and described in detail for purposes of explanation. It will be apparent, however, that the utility of the invention is not limited to rectifier tubes and that the new structure is of wider application.

The rectifier tube, in which the new cathode is to be used, has an anode of hollow cylindrical form into which the cathode projects. The cathode ordinarily includes a plurality of filaments of tungsten wire, for example, which are supported on rods extending through one end wall of the tube and terminating within the anode.

The copending application of Skehan and Magnusson, Ser. No. 596,038, filed May 26, 1945, discloses a filament assembly, which may be advantageously used in a rectifier tube having a hollow cylindrical anode, and, in the construction of that application, each filament is anchored at each end to a pair of fixed supports angularly offset by 180°, for example, so that each filament is of generally helical form. The filaments are of such shape and length, when cold, that, upon being heated, they expand to the desired final form, in which they are properly spaced from the anode.

The cathode structure of the present invention affords certain of the advantages of the structure of the copending application but differs therefrom in that the filaments are mounted in such manner that a less number of junctions of the filaments to their supports is required. The supports are also easier to make and, because of these differences, it is easier to control the electrical characteristics of the present structure.

For a better understanding of the invention, reference may be made to the accompanying drawings, in which

Fig. 1 is a view in longitudinal section of a rectifier tube provided with the cathode filament structure of the invention;

Fig. 2 is a sectional view on the line 2—2 of Fig. 1;

Fig. 3 is a view in side elevation on an enlarged scale of the new filament structure shown in Fig. 1;

Fig. 4 is a view similar to Fig. 3 but at right angles thereto; and

2

Fig. 5 is an end view of the structure shown in Fig. 3, looking from the left hand end thereof.

Referring now to the drawings, the tube shown in Fig. 1 comprises a glass envelope 10 having an enlarged central portion 10a and necks 10b of reduced diameter having re-entrant ends 10c, 10d. A metal cup 11 is sealed to the end 10c of one of the necks to close that end and a block 12 of suitable metal, such as steel, is mounted in the exposed bottom of the cup. A screw 13 is threaded into block 12 to contact with the cup 11 and a conductor 14 is connected to the screw and through it to the cup. A block 15 of suitable metal is mounted to enclose the end of cup 11 within the tube and a cylindrical metal shield 16 is mounted on the block to enclose the seal between the rim of the cup and the envelope wall. A plurality of metal rods 17 extend through openings in block 15 and are connected at their outer ends to cup 11. The cup 11, blocks 12 and 15, metal shield 16, and rods 17 are united, as by brazing, to form an integral assembly. The inner ends of rods 17 extend into one end of a cylindrical anode 18 and are connected thereto. The anode lies coaxially with the envelope and within the enlarged central portion 10a of the envelope.

A plurality of metal supporting rods lying in a plane and extending axially of the envelope are sealed through the closed end of the re-entrant portion 10d of the envelope and the rods are maintained in proper spaced relation by a block 19 of insulation, through openings in which the rods extend. The outer two rods 20, 21 terminate just within the end of the anode near end 10d of the envelope, while the remaining three rods 22, 23, 24 extend through the anode nearly to the opposite end thereof. The short rods 20, 21 and the central long rod 23 are for filament supporting purposes, while rods 22 and 24 serve both as filament supports and as conductors. The outer ends of rods 22 and 24 are, accordingly, connected to conductors 25a, 25b by which the filaments of the cathode are supplied with heating current and maintained at the proper potential difference relative to the anode. Rod 23 carries a sleeve 26 to which is attached a cup 27 shielding the seals of the rods through the envelope wall.

A metal strap 28, preferably of sheet molybdenum, is mounted on the end of each of rods 22, 24 and extends outward therefrom, the two straps being aligned. Each strap is formed at one end with a loop 28a, which is fitted around the end of a rod 22, 24 and welded thereto, and at its other end, the strap is formed with a smaller loop 28b. The central rod 23 carries at its free

end a cross-piece in the form of a double strap 29 made of two strips of sheet molybdenum riveted face to face and formed with a central opening 29a for reception of the end of rod 23. The double strap is welded to the end of rod 23 and at its outer ends, the strap is formed with loops 29b. Strap 29 extends at right angles to strap 28 and loops 28b and 29b are spaced equal distances from the axis of rod 23.

A sleeve 30 is mounted on the free end of each of rods 20, 21 and welded thereto. Each sleeve 30 is provided with an integral strap 30a extending outwardly from the axis of the rod on which it is mounted, and each strap 30a terminates in a loop 30b lying in axial alignment with a loop 28b on a strap 28.

A filament 31 of tungsten wire, for example, has one end received in and welded to the loop 28b of one of the straps 28 and the filament passes through the loop 30b on the strap 30a of one of the sleeves 30. The filament then extends to the adjacent end of the double strap 29 and its end is received in and welded to the loop 29b on strap 29. A second filament is similarly connected at its ends to the loop 28b on the other strap 28 and to the loop 29b at the other end of the double strap 29. Between its ends, the second filament passes through the loop 30b on the strap 30a of the other sleeve 30. With this arrangement, the ends of each filament are angularly offset 90°, while its mid-portion is offset angularly by 90° from one end of the filament and by 180° from the other. The ends of the filament are welded to the end of one strap 28 and to one end of the double strap 29 and only two welds are required for each filament. It is, therefore, relatively easy to maintain close control over the points of electrical contact of the filaments to the straps and thus avoid variations in the electrical characteristics of the filaments.

In the filament structure described, current supplied through conductor 25a, for example, flows through rod 24 to the strap 28 mounted thereon, and thence through the filament 31 attached to the end of the strap to one end of strap 29. The current flows through strap 29 to one end of the other filament 31 and through the filament to the end of the other strap 28. The current flows through the second strap 28 to the rod 22 and to conductor 25b.

Since the central portion of each filament is angularly offset from the ends of the filament, the lengths of each filament from each end support 28b, 29b therefore to the central support 30b are of generally helical form and are unequal. These lengths of the filament may, accordingly, be formed, in accordance with the disclosure of the copending application of Skehan and Magnusson above identified, so that, when, in the cold condition, they lie inward from the positions that it is desired that they may occupy when they are heated and expanded. The positions of the hot expanded filaments, relative to the anode, may thus be controlled, so that most satisfactory operation of the tube may be obtained.

I claim:

1. In a cathode filament structure, the combination of a pair of fixed supports laterally spaced from and angularly spaced about the axis of the structure, a third support spaced longitudinally of the structure from the pair of supports and lying spaced angularly about said axis from said supports and at the same side of both said supports, and a filament attached rigidly at its ends

to the respective supports of the pair and anchored between its ends to the third support.

2. In a cathode filament structure, the combination of a pair of fixed supports laterally spaced from and angularly spaced about the axis of the structure, a third support spaced longitudinally of the structure from the pair of supports and lying spaced angularly about said axis from said supports and at the same side of both said supports, a loop attached to the third support, and a filament attached rigidly at its ends to respective supports of the pair and passing through the loop on the third support.

3. In a cathode filament structure, the combination of a pair of fixed supports laterally spaced from and angularly spaced about the axis of the structure, a third support spaced longitudinally of the structure from the pair of supports and lying spaced angularly about said axis from said supports and at the same side of both said supports, and a filament attached rigidly at its ends to respective supports of the pair and having a portion between its ends secured to the third support, the parts of the filament between the third support and each support of the pair being of generally helical form.

4. In a cathode filament structure, the combination of a pair of fixed supports laterally spaced from and angularly spaced about the axis of the structure, a third support spaced longitudinally of the structure from the pair of supports, and a filament attached rigidly at its ends to the respective supports of the pair and secured between its ends directly to the third support, the third support being angularly offset about the axis of the structure from the pair of supports and lying at the same side of both supports the portions of the filament between the third support and those of the pair being of unequal length.

5. In a cathode filament structure, the combination of an even number of supports arranged in a series about a central axis, half as many other supports spaced along the axis from the series of supports and disposed about said axis, a plurality of filaments, each rigidly attached at its ends to adjacent supports in the series and between its ends to one of said other supports which is spaced angularly about the axis from said adjacent supports and lies at the same side of both said supports.

6. In a cathode filament structure, the combination of four supports arranged in a series about a central axis, two alternate supports in the series being electrically connected, a pair of supports spaced along the axis from the series of supports and lying on opposite sides of said axis, and a pair of filaments each connected rigidly at one end to a pair of adjacent supports in the series and between its ends to a support of the pair which lies offset about the axis at the same side of said adjacent supports to which the ends of the filament are secured.

7. In a cathode filament structure, a group of five rods lying side by side in spaced relation in a plane, the two outer rods being shorter than the three inner ones, a strap attached to each short rod and terminating in a loop offset outwardly from the axis of the rod in said plane, a member mounted on the end of each outer long rod and extending outwardly therefrom in said plane, each member terminating in a sleeve aligned with one of said loops, a cross-piece attached to the end of the central long rod and extending at right angles to said plane, said cross-

piece having terminal sleeves lying in a circle passing through the sleeves on said members, and a pair of filaments, each having one end secured in the sleeve on one member and its other end secured in the sleeve at one end of the cross-piece, the filament passing through a loop on the short rod at the opposite side of the group from the long rod carrying the member in the sleeve of which one end of the filament is received.
